(57) **CLAIM**

The ornamental design for a vehicle, as shown and described.

DESCRIPTION

FIG. 1 is a perspective view of a vehicle showing our new design;

FIG. 2 is another perspective view viewed from the opposite side thereof;

FIG. 3 is an enlarged front elevational view thereof;

FIG. 4 is an enlarged rear elevational view thereof;

FIG. 5 is a side elevational view of one side thereof;

FIG. 6 is a side elevational view of the opposite side thereof; and,

FIG. 7 is a top plan view thereof.

The broken lines and unshaded areas depict portions of the article that form no part of the claimed design.
